(57) **CLAIM**

The ornamental design for a phalangeal splint, as shown and described.

DESCRIPTION

FIG. 1 is a top view of a first embodiment of a phalangeal splint, showing my new design;
FIG. 2 is a front view thereof;
FIG. 3 is a bottom view thereof;
FIG. 4 is a rear view thereof;
FIG. 5 is a left side view thereof;
FIG. 6 is a right side view thereof;
FIG. 7 is bottom-left-front perspective view thereof;
FIG. 8 is a bottom-right-front perspective view thereof;
FIG. 9 is a bottom-left-rear perspective view thereof;
FIG. 10 is a top view of a second embodiment of a phalangeal splint of FIG. 1;
FIG. 11 is a front view thereof;
FIG. 12 is a bottom view thereof;
FIG. 13 is a rear view thereof;
FIG. 14 is a left side view thereof;
FIG. 15 is a right side view thereof;
FIG. 16 is bottom-left-front perspective view thereof;
FIG. 17 is a bottom-right-front perspective view thereof;
and,
FIG. 18 is a bottom-left-rear perspective view thereof.
